UNITED STATES PATENT OFFICE

EDWIN FITCH NORTHRUP, OF PRINCETON, NEW JERSEY, ASSIGNOR TO AJAX ELECTROTHERMIC CORPORATION, OF AJAX PARK, TRENTON, NEW JERSEY, A CORPORATION OF NEW JERSEY

HEATER FOR RODS AND TUBES

Application filed March 15, 1930. Serial No. 436,193.

My invention relates to the inductive heating of solid and tubular articles both fixed and movable and to apparatus by which these methods may be practiced. The subject matter herein is a continuation in part of my copending application, Serial Number 76,878, filed December 21, 1925 for heater for rods and tubes.

Application 76,878 is in turn a continuation in part of the subject matter of my application, Serial No. 425,439, filed November 20, 1920, resulting in Patent No. 1,566,500, issued December 22, 1925, and with which said application 76,878 was copending. The subject matter of Figures 17 and 18 of the patent has been continued through application 76,878 and affords basis—subject to the lines of division required by the United States Patent Office—for claims of the present application.

One of the purposes of my invention is to surround solid or tubular articles with a conductor through which high frequency current produced by a discharge gap is to be passed, and to heat them by the current induced preferably while they are passing through the coils but permissibly during stops in step-by-step feeding.

A further purpose is to apply induction to a moving rod or tube by a coil or coils surrounding the rod or tube and through which current from a discharge gap is passed having a frequency above normal frequencies and a corrected power factor.

A further purpose is to provide parallel coils or turns all fed from the same discharge gap and all operating successively upon the same tube or rod fed through them for the purpose of adding successively increments of heat to the rod, strip or tube passing through them.

A further purpose is to use a relatively low frequency for inductive heating of rods, strips or tubes of magnetic material up to nearly the point at which they lose this property, to heat them beyond this point by a higher frequency from a discharge gap using the same inductor or part of the same inductor for both, either at the same time or separate times.

A further purpose is to supply power-factor corrected current from a generator of multi-polar rotary type to an inductor through which a charge is to be passed to a transformer primary, to utilize current from the secondary of this transformer raised in frequency by condensers and a discharge gap to supply higher frequency induction also surrounding the charge.

A further purpose where the voltage of the generator is sufficient to cause discharge across the gap is to supply an inductor surrounding the charge from a rotary multi-polar generator with condenser power factor correction and through another circuit containing inductance, capacity and a discharge gap to supply higher frequency induction for the same charge.

Further purposes will appear in the specification and in the claims.

I have preferred to illustrate a few forms only among many in which my invention may appear, selecting forms which best illustrate the principles of my invention.

Figure 1 is a longitudinal section of one form of inductor applied to a travelling bar or rod.

Figures 2, 3 and 4 are diagrammatic views showing different circuit connections.

In the drawing similar numerals indicate like parts.

Though I prefer to operate at a higher frequency than that of existing current supplies and gain considerable advantage from this, features of my invention are of advantage whatever the frequency and are claimed accordingly.

In Figures 1 to 4 I have shown different ways in which current at more than normal frequency can be supplied to an inductor comprising a single coil or spaced coils operating upon the same moving bar, rod, strip or tube of regular or irregular shape, or to a conducting content, to raise it to the required temperature as for rivet heating, tube or strip annealing or for other operations. By these different illustrations I have intended to indicate that the use of abnormal frequency to this duty involves invention.

in addition to whatever merit may lie in the manner of applying it.

In Figure 1 I have shown a method of integrating the heating effects of successive coils through which high frequency current is passed in the heating of a bar or rod which is advanced to progress either continuously or intermittently as preferred, as by a set of rollers 20 and 21 suitably mounted and driven. The coils 22, 23, 24, 25 and 26 are here shown as helical coils nearly fitting the bar, wire, rod or strip 27 which moves in the direction of the arrow. I have not considered it necessary to illustrate the protecting covers 15 for preventing undue cooling of the bar etc., between the coils, as these could exist in great variety. The coils could be water-cooled if desired as in the case of the annular coils shown in my patents.

20 The coils are shown as separate and as separately supplied with high frequency current through transformers 28 whose primaries 29 receive current at existing frequencies. The secondaries are connected to the coils through 25 condensers 30 which when charged discharge across gaps 31. They can be one long coil or a series of coils depending upon the rate of speed of the charge.

It will be evident that the methods and 30 mechanism herewith are capable of use generally or to heat treat electrically conducting objects in motion or which are moved step-by-step between treatments, whether they be magnetizable or not; and that the treatment 35 may be applied to the special form of objects to be treated by accommodation of the coils in shape to these forms. The materials primarily to be treated when not electrically conducting may be treated by mounting them on or incasing them within electrically conducting objects in which the heat is developed. Muffle heating is claimed by me in a separate application.

Where the temperature intended to be 45 reached is below the point at which iron or steel loses its magnetic properties a much lower frequency will suffice than is required where the final temperature intended is above this point, with the result that a choice is offered for these higher temperatures between raising the frequency of the entire 50 equipment to a frequency which will be effective above the decalescence point or raising the temperature in a part of the range required by an inductor operating at one frequency and utilizing another higher frequency through the same or a separate inductor coil or coils to attain the higher temperatures.

It is very desirable that the frequency shall 60 be high enough so that the energy induced shall not pass appreciably beyond the center of a solid bar or rod operated upon nor tend to pass appreciably beyond the inner wall of a tube which is being heated, and, as later 65 pointed out, the size of stock operated upon

therefore materially affects the choice of frequency.

It is my intention to include within my generator supply such generators and such use of frequency changers as may best suit 70 the needs of the individual installation.

In Figure 2 I have shown direct alternator feed with power factor correction at 32 for the inductor coil 22' shown, fed through a transformer 28' whose secondary is connected 75 to a circuit generally similar to any of those shown in Figure 1, containing the condensers 30 and gap 31 for applying high frequency to the coil. In this same coil also flows low frequency from the transformer 33 80 whose power factor is corrected at 34. The high frequency is then superimposed on the low frequency in the same coil. Either the high or low frequency can be used separately.

In Figure 3 the lower frequency is passed through the coils 22², 23² and 24² from the current source 35, having its power factor corrected at 36. The last coil 24² also carries higher frequency supplied from the transformer 28², by the use of a gap 31 and condensers 30, generally similar to any of the circuits of Figure 1.

In Figure 4 the low frequency coil 22³ is supplied from the line with power factor correction at 37, while the higher frequency coil 23³ is supplied from a circuit generally similar to any of those in Figure 1, including power factor correction at 32', as well as condensers 30 and a gap 31.

The form shown in Figures 2 and 3 would 100 be used where the voltage of the supply line is not high enough to operate the discharge gap.

Where the voltage of the generator 35' is high enough to operate the discharge gap 31, 105 the arrangement shown in Figure 4 is permissible. Here part of the inductor 22³ is supplied directly from the generator, with power factor correction, and a further part 23³ of the inductor is fed through condensers.

Instead of directly heating the stock, I may heat an electrically conducting muffle and pass the stock through the muffle.

In all of the forms where a plurality of turns per coil is used, I prefer to use a single layer coil of edgewound flattened copper tubing and find water cooling of the tubing very desirable.

In operation upon stock of the character 120 treated herein, whether it be solid or hollow, of uniform or of irregular cross-section, the coupling increases with increased diameter of the stock as the gap required is approximately constant.

The frequency desirable reduces with increase of the diameter or with increased thickness of the stock since it is desirable not to have effective induction extend beyond the center of the stock. This would apply 125

also to the center of the core or muffle where these are used. The formula for determining this frequency is

$$5 \quad N = \frac{25 \times 10^{-6} \rho}{\mu l^2}$$

where N is the frequency, ρ the resistivity of the material, μ the permeability and l^2 is the "depth of penetration", approximating one-third of the distance to which the induction extends.

The higher frequencies have the advantage of requiring less capacity to correct the power factor, but have the disadvantage of requiring special generators or other equipment to supply the current. With magnetic materials low frequencies can be used even on relatively small diameters of stock; but when the stock is non-magnetic, unless it be 20 large in diameter, high frequencies must be used if too deep penetration of induction into the stock is to be avoided.

My invention is independent of the number of turns per coil and of the detail of the 25 coil and can be applied with loops as distinguished from turns, with loops in series or in parallel, with coils, single, in series or in parallel and with great variety of current supply. I prefer to water cool the coils and where the inductor coil comprises more 30 than one turn, I prefer to use conductors having one dimension considerably greater than the other in cross-section and with the greater dimension radial to the axis of the coil, 35 whether the coil be water cooled or not.

My invention is applicable to magnetic or non-magnetic materials whether solid or otherwise and to heating of hollow or solid materials directly by the RI^2 heat development in the materials themselves, wholly or in part, by heat conduction and radiation from a casing or core or muffle within which RI^2 heat is developed.

In operation the material to be heated may 45 be progressed through the coil or through one about the muffle, step-by-step or continuously or, much less desirably, may be inserted therein and withdrawn. Considering the continuous operation, by odds the most 50 advantageous form, the object or material to be heated is fed through at a rate such that with the energy available and at the frequency determined upon, it will reach the required temperature or a temperature just 55 high enough to be at the proper temperature at the point of use as it emerges from the final coil or turn. Heating magnetic material to the point at which it begins to lose its magnetism may be effective at a relatively 60 low frequency though, with small stock, or because of expense of power factor correction, very desirably at a frequency higher than available from line sources of supply and heating beyond the decalescence point will be 65 performed at a much higher frequency.

Where the material is non-magnetic and unless assisted by the inclusion of magnetic material in the form of a muffle or core the heating will be performed wholly at a higher frequency than that of available line sources of 70 supply.

In view of my disclosure herein other forms and uses of my invention will undoubtedly occur to those skilled in the art differing from mine in adaptation to special uses, suiting the 75 preference or whim of the individual designer or for the purpose merely of avoiding copying of my forms and it is my purpose to include herein all such as come within the reasonable spirit and scope of what I regard 80 as a very broad invention.

Having thus described my invention what I claim as new and desire to secure by Letters Patent is:—

1. In the art of electric heating, a source 85 of alternating current supply, a plurality of helical coils having their axes in line, connections from the source of supply separately to each coil, capacitative means within said connections and a plurality of discharge gaps, 90 one across the coils for supplying high frequency oscillations to the coils from said current supply.

2. In the art of inductive electric heating, a 95 commercial source of alternating current, an inductor coil connected therewith, a circuit including the source and coil power factor corrective means connected with the circuit to offset the inductance of the coil, a transformer primary fed by said source, a transformer secondary in inductive relation to the primary, a second inductor coil axially in line with the first and fed from said transformer secondary, capacity in the circuit between 100 said secondary and second coil, a discharge gap across the circuit of said secondary, converting the frequency of the current supplied by said secondary to a higher frequency and means for passing an electrically conductive 105 article to be heated through said coil to receive successive increments of heat by induction from the current therein.

3. In the art of inductive electric heating, 110 a pair of inductor coils, a source of alternating current of commercial frequency, connections for one of said coils across the source of supply from said source, condenser power factor corrective means for said coil, a transformer primary connected with said source, a 115 transformer secondary in inductive relation to the primary, wholly separate connections from the secondary for the second coil, including a discharge gap and condensers, and means for passing an electrically conductive 120 article to be heated through said coil to receive successive increments of heat by induction from the current therein.

4. In the art of electric induction heating, 125 a source of alternating current of commercial frequency, an inductor coil across the 130

source of supply of said source, power factor corrective means for said inductor coil, a second inductor coil, connections for the second coil, also across the line of said source 5 and including capacity and a discharge gap across which the voltage of the source is sufficient to cause discharge and means for passing an electrically conductive article to be heated through said coil to receive successive 10 increments of heat by induction from the current therein.

5. In the art of inductive electric heating, a hollow helical coil, a source of electric current therefor, means including a discharge 15 gap and a condenser for supplying high frequency therefrom to the coil and supporting means for moving an article to be heated having larger length than width or thickness through the coil while it is being subjected 20 to the heating effect of the coil.

6. In the art of inductive electric heating, a hollow helical coil, a source of electric current therefor, transformer means for applying current of the frequency of the source 25 to said coil, means including a discharge gap and a condenser for applying a higher frequency from the source to said coil and supporting means for an article to be heated and moved lengthwise through said coil.

30 7. In the art of inductive electric heating, a plurality of coils axially aligned, a source of alternating current therefor, means including a discharge gap and a condenser for increasing the frequency of current fed from 35 the source of current through said coils, and means for supporting an article to be heated so that it can be moved through the coils and receive the cumulative effect of the current induced by said coils.
